CAP OR THE LIKE

Hettye S. Lazarus, New York, N. Y.

Application February 5, 1949, Serial No. 697

Term of patent 14 years

(Cl. D3—13)

To all whom it may concern:

Be it known that I, Hettye S. Lazarus, a citizen of the United States, residing at New York, in the county of New York and State of New York, have invented a new, original, and ornamental Design for a Cap or the like, of which the following is a specification, reference being had to the accompanying drawing, constituting a part thereof.

Fig. 1 is a perspective view of a cap, showing my new design;

Fig. 2 is a side view thereof; and

Fig. 3 is a perspective view thereof as it appears in folded position.

I claim:

The ornamental design for a cap or the like, substantially as shown.

HETTYE S. LAZARUS.
